UNITED STATES PATENT OFFICE

2,494,100

DISPLACEMENT MECHANISM

John Mikulasek, Bellevue, Iowa

Application March 27, 1944, Serial No. 528,304

3 Claims. (Cl. 230—146)

1

This invention relates to a fluid displacement device that may be put to numerous uses either as a suction pump or a pressure pump, such a device also being constructed to act as a motor by supplying a fluid under pressure thereto.

The object of this invention is to provide a device of the class mentioned having a plurality of spiral blades in each set, thereby decreasing the radial distances between the adjacent convolutions of the blades for increasing the efficiency of the device.

All other features and advantages inherent in the fluid displacement device presented shall hereinafter be referred to in the more detailed description of the device disclosed which carry out the principles of the present invention, reference being had to the accompanying drawings wherein the mechanical adaptations of the principles are illustrated. In the drawings:

Fig. 1 is a cross sectional view taken substantially upon the line 1—1 of Fig. 2 illustrating a construction involving this invention.

Fig. 2 is a vertical sectional view taken substantially along the line 2—2 of Fig. 1.

In referring now to the drawing which illustrates a preferred form of this invention, there is shown a pump casing 40 which consists of two sections 41 and 42, and openings for fluid passage into and out of the displacement device provided as at 43 and 44. Stationary spiral blades 61, 62 and 63 are attached to casing section 42 and extend within the casing. Movable spiral blades 64, 65, and 66 are carried by a free disk 67 which extends in parallel relation to the casing section 42.

The disk 67 with its attached blades is operated by eccentric mechanism; this is possible because of the shortness of the stroke which is made possible by the use of a plurality of three blades, a construction which decreases the radial distances between the adjacent convolutions of the blades. In the construction illustrated, the eccentric operating mechanism for oscillating the movable blades comprises three eccentrics 68, 69 and 70, which are respectively carried by shafts 74, 75 and 76 journaled in the casing. The inner terminals of the movable blades are provided with bearing sleeves 71, 72 and 73 respectively for encircling the eccentrics which it will be noted are located in the casing. Each of the shafts 74, 75 and 76 carries a counterbalanced gear 77 outside of the casing. A driving gear 78 which is secured to a shaft 79 meshes with the three gears 77. The inner end of the shaft 79 is journaled in the casing and counterbalancing members 80

located beyond the spirals for reducing vibrations under high speed operation may be provided upon shafts 74, 75 and 76.

In the operation of this device, it will be seen that, during the operation of the shafts 74, 75 and 76, the eccentrics will oscillate the movable blades with respect to the stationary blades for opening and closing the gaps between the stationary and movable blades for producing a pumping action.

The construction is exceedingly simple and efficient as it is well balanced and not likely to get out of proper balance during operation whereby the parts will always maintain a proper relationship.

There are numerous other adaptations of the principles of the present invention and those which have been described and disclosed and those which have been so presented do fairly well represent such basic structures of this invention.

A pump of this type may be readily manufactured within reasonable tolerances in spite of the fact that involute curved blades are used, the main consideration in the construction of such blades being to maintain the radial distances between adjacent convolutions equal in distance to obtain the greatest efficiency in the pump during performance. The thickness of the blades may be the same in each set, although the blades of one set may be made considerably thicker than the blades of the other set which may be desired under certain conditions of materials.

One of the other features of the present invention is that the structures hereinbefore described are all such that when the same are put to the use of driving some other unit as a motor that no dead center relationship exists at any time. In other words, the minute pressure is applied to the pump blades, preferably through the center opening thereof, the movable blades shall be set into motion immediately regardless of their position angularly with respect to the axis of the pump which produces a unit which is very versatile in its operation and adaptation.

Other changes and variations in the design, construction, and the combination of parts of this fluid displacement device are contemplated. Therefore, the invention is not to be limited to the exact disclosure and description presented excepting insofar as the same shall be limited by the appended claims.

What I claim is:

1. In a device of the class described, a casing having side walls, a plurality of spiral blades

extending inwardly from one side wall, a disk adjacent the other side wall, spiral blades carried by said disk in operative relation with the first mentioned blades, the blades on said disk having bearing sleeves at their inner terminals, elongated eccentrics extending through said sleeves, shafts journaled in said casing and carrying said eccentrics and means for operating said shafts.

2. In a device of the class described, a casing having side walls, a plurality of spiral blades extending from one of said side walls, a disk adjacent the other side wall, a plurality of spiral blades carried by said disk in operative relation with said first mentioned blades, the blades on said disk having integral bearing sleeves upon their inner terminals, eccentrics journaled in said sleeves shafts extending through said casing and carrying said eccentrics and counterweights upon said shafts adjacent the sides of said spiral blades and means for operating said shafts.

3. In a device of the class described, a casing having side walls, a plurality of spiral blades extending from one side wall, a free disk adjacent the other side wall, a plurality of spiral blades carried by said disk in operative relation with the first mentioned blades, the blades on said disk having sleeve bearings upon their inner terminals, shafts journaled in said casing and having eccentrics journaled in said sleeve bearings, counterweights on said shafts adjacent said

spiral blades, counterbalanced gears carried by said shafts and a common gear for operating said gears.

JOHN MIKULASEK.
